UNITED STATES PATENT OFFICE.

LYBRUN ANDERSON, OF WASHINGTON, DISTRICT OF COLUMBIA, ASSIGNOR
TO HIMSELF, LEWIS H. SCHNEIDER, AND JOHN MARTIN, OF SAME PLACE;
SAID SCHNEIDER ASSIGNS HIS RIGHT TO SAID ANDERSON AND MARTIN.

IMPROVEMENT IN PIPE-WRENCHES.

Specification forming part of Letters Patent No. 124,654, dated March 19, 1872.

To all whom it may concern:

Be it known that I, LYBRUN ANDERSON, of Washington, in the county of Washington and in the District of Columbia, have invented certain new and useful Improvements in Pipe-Wrenches; and do hereby declare that the following is a full, clear, and exact description thereof, reference being had to the accompanying drawing and to the letters of reference marked thereon making a part of this specification.

The nature of my invention consists in the construction and arrangement of a "pipe-wrench," as will be hereinafter more fully set forth.

In order to enable others skilled in the art to which my invention appertains to make and use the same, I will now proceed to describe its construction and operation, referring to the annexed drawing, in which—

Figure 1 is a side view of my wrench, part in section, and Figs. 2 and 3 are views of different holders inserted in the wrench so as to make it suit thin or thick pipe.

A and B represent the two jaws of my wrench, pivoted together, as shown, and forming on the other side of the pivot handles C C. The jaw A is formed in hook shape, while the jaw B has a perfectly-flat surface; and in the front part of this latter jaw is a square recess, socket, or chamber for the reception of holders D or E. The holder D has a square end or shank to fit in the socket in the jaw B, and its outer end is enlarged somewhat in the shape of a foot, as shown in Fig. 2. The under side of this part of the holder D is toothed so as to grasp the pipe firmly without any very severe pressure upon the handles. This is necessary in turning brass pipes or other pipes made of thin metal, as they will not bear any very hard pressure. The holder E is also, at one end, shaped so as to fit in the recess of the jaw B, while the other end is a beveled flat surface. Both the holders D E are provided with a longitudinal groove, *a*; and a set-screw, *b*, is passed through the jaw B into said groove to prevent the holder from falling out. It will, however, be noticed that there is no strain in using the wrench upon this set-screw. The strain is entirely upon the jaw itself, as the holder rests upon the bottom of the recess in the jaw B.

If the holders should become worn, or if, for any other purpose, it should become necessary to lengthen the holder, small pieces of metal may be laid in the bottom of the recess and the holder placed on top of the same.

It will be seen that the walls of the lateral recess formed in the jaw B are made on a line parallel with the front end of said jaw, and that the steel dies or holders D or E are made to fit neatly within in said recess, and are inclined on their outer faces, forming a gripping-point, so that, when the jaws A and B are separated from each other to receive the pipe, the point or front end of the die and the hook of the jaw A are on an oblique line from each other. By this construction I am enabled to more effectually gripe and take hold of the pipe, and more easily engage or disengage the sections thereof to or from each other.

It will be understood that the wrench-handles and jaws are made of wrought-iron or brass, or similar inexpensive metal, while the die or holder I use is made of a solid block of cast-steel; and that it is not my intention to have the die adjustable within its recess to accommodate different sizes of pipe, as I propose to have a wrench for each of such sizes. My only object in providing the die with the groove *a* on its front is for the purpose of allowing it to slide from the base of the recess in the jaw as its front becomes worn, and to place a wedge behind it, and to replace the die by a new one when, after long use, it is rendered useless.

I am fully aware that a pipe-wrench consisting of two jaws, with one or both of said jaws faced with steel, is not new, as such is in common use. My wrench is intended to obviate the necessity of such face-plating of steel. I am also aware of the existence of a pipe-wrench composed of two jaws, one hooked and the other having a flat steel face-plate, with a dovetailed tongue fitting into a corresponding groove in the other jaw, by which the same is forced outward or drawn inward by a set-screw attached to its extremity nearest the handles. I am also aware of a wrench having one hooked jaw and the other jaw provided with an outward-sliding die, secured in a metallic stirrup attached to said jaw and held in place by a key; but, none of these cases being similar in construction, and not possessing the advantages in op-

eration that I conceive mine to have, I disclaim such to be my invention.

What I claim, and desire to secure by Letters Patent, is—

The combination of the hooked jaw A with the jaw B pivoted thereto, and provided with a lateral recess near its front end and the steel die or holder D, (or E,) inclined on its face, (at x,) as shown, and having a slot, a, on its front, by which it is held in the recess by the screw b

on an oblique line to the hook of the jaw A, all substantially as and for the purposes set forth.

In testimony that I claim the foregoing I have hereunto set my hand this 19th day of July, 1871.

LYBRUN ANDERSON.
